UNITED STATES PATENT OFFICE.

EDWIN H. MESSITER, OF BROOKLYN, NEW YORK, ASSIGNOR TO ELECTRIC WEIGHING COMPANY, OF NEW YORK, N. Y., A CORPORATION OF NEW YORK.

ELECTRIC METER.

1,221,560.

Specification of Letters Patent.

Patented Apr. 3, 1917.

Application filed August 12, 1913. Serial No. 784,342.

To all whom it may concern:

Be it known that I, EDWIN H. MESSITER, a citizen of the United States, and a resident of the borough of Brooklyn, county of 5 Kings, and State of New York, have invented certain new and useful Improvements in Electric Meters, of which the following is a specification, reference being had to the accompanying drawings, forming a part 10 thereof.

My invention relates to electric meters of the rotary type and its object is to improve upon instruments of this character and to make them more reliable and efficient.

Another object is to provide a simple arrangement for adjusting the action of such 15 meters.

Other objects of my invention will appear in the following specification in which my 20 invention will be described, the novel features of which will be set forth in appended claims.

Referring to the drawings,

Figure 1 is a front elevation, partly in 25 section, of a meter embodying my invention.

A detail of construction is shown in Fig. 2 which is an enlarged sectional elevation of a circuit closing device which forms a part of and is embodied in the apparatus 30 shown in Fig. 1.

A device arranged to be controlled by the circuit closer of the meter is shown more or less diagrammatically in elevation in Fig. 3.

Fig. 4 is a wiring diagram of connections 35 between the meter and the device illustrated in Fig. 3.

Fig. 5 is a sectional plan view of the meter shown in Fig. 1, the section being taken 40 on the line 5—5 of Fig. 1 and illustrating more particularly the arrangement of the motor magnets.

The construction of a part of the damping device is shown clearly in sectional front 45 elevation in Fig. 6 and in plan in Fig. 7.

Fig. 8 is a plan view showing a modified construction of the part shown in similar view in Fig. 7.

The driving disk is shown in plan view in 50 Fig. 9, and its construction more specifically

illustrated in Fig. 10 which is a sectional elevation on an enlarged scale of a portion of the driving disk.

Like characters of reference designate 55 corresponding parts in all the figures.

The frame of the meter, designated by 10 is made of non-magnetic material such as brass. This is constructed to support the motor magnets 11,—preferably four double magnets held in some such relative fixed positions as shown in Fig. 5. The ends of 60 these magnets are provided with flat faced projecting pole pieces 12. The upper pole piece of each magnet approaches the under pole piece of the same magnet leaving between them a narrow horizontal space in which the rotor disk 20 is placed.

Supported upon the frame 10 is a circular disk 13 of mica or the like in the center of which is supported an inverted cup-like 70 guide bearing 14 which may be secured thereto by nuts as shown. 15 is an annular spacing washer above which is another circular insulating washer 16. Above this is a block 17 of insulating material in the center 75 of which is a circular hole which forms a float chamber. These parts are securely clamped together and to the frame by any suitable means such as screws or bolts (not shown). The float chamber is filled with 80 mercury 18.

The rotor disk 20 is mounted upon a vertical shaft 21. Above the disk is the float 22 the buoyancy of which in the mercury supports the weight of the shaft and the 85 parts on it. The shaft is guided at its lower end by the bearing 14 and at its upper end by a bearing 23 in a yoke 24 which is secured to the frame 10.

The rotor disk 20 is provided with radial 90 cuts 25 which are filled with insulating material as is shown in Fig. 10 so that its upper and lower surfaces are smooth. Cuts of this kind have heretofore been provided in rotor disks of this character for the purpose 95 of causing the measured current which passes through the disk to pass more or less diagrammatically across the disk instead of spreading out through its entire body. Such cuts however increase the friction of 100

the disk as it rotates in the body of mercury as they tend to throw the mercury outward in the manner of a centrifugal pump and as this resistance to the rotation of the disk increases rapidly as the rate of rotation increases it has seriously detracted from accuracy of the device as a measuring instrument. By filling the cuts however, as herein disclosed, I retain the advantage of the cuts without their heretofore attendant disadvantage.

The damping disk 30 is mounted on the shaft 21 to rotate between the pole pieces of the damping magnets 31. These as shown are preferably four in number, supported by the frame 10 and disposed in substantially the same relative positions as are the motor magnets.

The pole pieces as shown in detail in Fig. 6, are designated by 32 and are affixed to adjacent ends of facing magnets. In order to increase their effect, their surfaces which are nearest the disk are ribbed with corresponding high portions opposite one another. These ribs may be radially disposed as shown in Fig. 7, or if preferred they may be parallel with one another as shown at 32^a in Fig. 8. In either case they tend to concentrate the magnetic flux of the magnets in lines substantially transverse to the movement of the disk and to reduce the eddy current losses, thereby increasing the damping effect.

Affixed to the insulating block 17 is the flange 40 which supports a hollow vertical sleeve 41. The shaft 21 passes through this sleeve and the outer surface of the sleeve is threaded to adjustably support a horizontal regulating disk 42 of magnetic metal. Near the periphery of this disk are drilled at regular intervals vertical holes which can be brought into register with a similar hole in a graduated bracket 43. By rotating the disk it may be raised or lowered into a desired position and held there by means of a wire 44 passing through the hole in the bracket 43 and through one of the holes in the disk and fastened by a seal 45.

Affixed to the yoke 24 is a cross piece 50 which supports one or more reservoirs 51 adapted to hold mercury. A mercury cup 52 is connected with each of these reservoirs by a tube 53, the opening through which is of capillary dimensions. The mercury in the cup forms a meniscus 54 which projects above the upper edge of the cup.

Affixed to the shaft 21 is a contact wire 55 the lower end of which passes through the mercury meniscus at every revolution of the shaft. This wire may be more rigidly supported by passing it through a block 56 on the shaft.

The various parts of this apparatus have been pointed out and I will proceed to describe its operation. The current to be

measured is passed through the instrument by conductors connected with the terminals A B (Fig. 5) which connect with the mercury 18 in which the rotor disk 20 is immersed. The disk is of copper or of some material of higher conductivity than is the mercury so that the greater part of the current traverses the disk diametrically and the slots in the disk tend to keep it from spreading out through the disk. As the disk is in a strong and practically constant magnetic field, it becomes the armature of an electric motor and rotates at a speed proportional to the strength of the current passing through it.

The damping disk 30 is rotated thereby in another strong magnetic field and this rotation tends to generate a current therein. The work done by rotating the damping disk opposes the driving effect of the rotor and tends to quickly bring the parts to rest as soon as the measured current is cut off.

The ribbed pole pieces of the magnets which provide the field for the damping disk concentrate the magnetic lines of force passing through the disk along lines transverse to the direction of rotation of the disk and increase the efficiency of this part of the apparatus.

The meter illustrated, in common with others of like type, comprises two sets of permanent magnets spaced apart. In the space between them, I place the regulating disk 42 of magnetic material. This diverts some of the magnetic lines of force from both sets of magnets. The nearer it is to the motor magnets, the more their effectiveness is diminished and their driving effect neutralized. At the same time the further the adjusting disk is away from the damping magnets, the more of their lines of force pass through the damping disk and its retarding effect is increased. Obviously the converse of these statements is true.

I have provided for a very delicate variation of the position of this disk and by moving it up or down the instrument may be adjusted to a nicety.

The shaft 21 may be connected to drive an indicator in the usual manner, but in order to get more accurate results, I prefer to omit such mechanisms with their attendant frictional losses and to use instead a circuit closing device for an auxiliary circuit.

Referring now to Figs. 3 and 4, 60 designates a battery one terminal of which is connected to the shaft 21 by a conductor 61. 62 and 63 are electro-magnets to one terminal of each of which is connected the other terminal of the battery. The other magnet terminals are connected with the reservoirs 51, 51 and through the mercury therein with the menisci 54, 54. When the meter shaft rotates, the conductor 55 will contact first with one meniscus and then with the other.

thereby establishing a circuit, first through one magnet and then through the other.

When magnet 62 is energized, it will pull armature 64 on the lower end of an arm 65 pivotally supported at 66, to the left. A double pawl 67 is connected with arm 65 and this movement of the armature causes the pawl to rotate a star wheel 68 one step in the direction of the arrow shown thereon.

10 Another half revolution of shaft 21 will cause a circuit to be closed through magnet 63. This pulls the armature over to the right, and through the parts just described, causes the wheel 68 to be rotated another 15 step in the same direction.

The indication or recording mechanism which is actuated by the meter is driven by the shaft 69 of the star wheel.

It is sometimes desirable to have other devices controlled by the magnets 62, 63 which may be done by causing the swinging movement of the arm 65 to close and open other circuits. A simple way of accomplishing this is to support a vacuum tube 70 on the 25 arm in such a position that it will be horizontal when the arm is in its central or intermediate position. Near the opposite ends of this tube are spaced contacts or terminals 71, 72 which pass through the tube and with 30 which wires may be connected. Within the tube is a small quantity of mercury 73 which, when the parts are in the positions in which they are shown in the drawings, will connect the contacts 72 and which when the 35 magnet 63 has drawn armature 64 over to itself will connect the contacts 71. Thus an alternate intermittent connection of two circuits may be established which may be utilized to actuate other registering or 40 recording devices.

The driving mechanism which is controlled by the meter and which actuates the indication or recording mechanism, forms the subject-matter of a separate application 45 Serial No. 856,917, filed August 15, 1914, which is a continuation in part of this application.

What I claim is:

1. In a meter, a motor mechanism having 50 a magnetic field, a damping mechanism having a magnetic field and arranged to oppose the effect of the motor mechanism and an adjusting device arranged to inversely vary the effective strength of said magnetic fields.
- 55 2. In a meter, a motor mechanism having a magnetic field, a damping mechanism having a magnetic field and arranged to oppose the effect of the motor mechanism, and a member of magnetic material arranged to divert a part of the lines of force of both 60 of said magnetic fields, and means for adjusting the position of said member relatively to said fields.
- 65 3. In a meter, a motor mechanism having a magnetic field, a damping mechanism hav-

ing a magnetic field and arranged to oppose the effect of the motor mechanism, and a member of magnetic material between said fields arranged to divert a part of the lines of force of both of said magnetic fields, and means for adjusting the position of said member toward one of said fields and away from the other field. 70

4. In a meter, a motor magnet, a damping magnet, and a member of magnetic material adjustably supported between said magnets and adapted to influence both magnets. 75

5. In a meter, a set of horizontally disposed motor magnets, a set of horizontally disposed damping magnets, and a vertically adjustable member of magnetic material between said sets of magnets and adapted to influence both sets of magnets. 80

6. In a meter, a shaft, a rotor disk thereon, means for producing a magnetic field for the rotor disk, a damping disk on said shaft, means for producing a magnetic field for the damping disk, a member of magnetic material between said magnetic fields arranged to divert a part of the lines of force of both of said fields, and means for adjusting said member in a direction parallel with the shaft to inversely vary the effective strength of said magnetic fields. 90

7. In a meter, a vertical shaft, a rotor disk thereon, means for producing a magnetic field for the rotor disk, a damping disk on said shaft, means for producing a magnetic field for the damping disk, a disk of magnetic material surrounding said shaft between said magnetic fields arranged to direct a part of the lines of force of both of said fields, and means for adjusting the vertical position of said member to inversely vary the effective strength of said magnetic fields. 95

8. In a meter, a vertical shaft, a rotor disk thereon, a stationary magnet for the rotor disk, a damping disk on said shaft, a stationary magnet for the damping disk, a threaded sleeve surrounding the shaft and an internally threaded disk of magnetic material on said sleeve between the magnets. 100

9. In a meter, a vertical shaft, a rotor disk thereon, a stationary magnet for the 115 rotor disk, a damping disk on said shaft, a stationary magnet for the damping disk, a threaded sleeve surrounding the shaft, an internally threaded disk of magnetic material on said sleeve between the magnets, 120 a graduated vertical scale at one side of said magnetic disk, and circumferential graduations on the disk.

10. In a meter, a vertical shaft, a horizontally disposed horse-shoe magnet, a rotor disk on the shaft between the poles of said magnet, another horizontally disposed horse-shoe magnet in a different vertical position, a damping disk on the shaft between the poles of said other magnet, an externally 130

threaded hollow stationary sleeve surrounding the shaft, and an internally threaded disk of magnetic material adjustably supported on said sleeve between the magnets.

5 11. In a meter, a vertical shaft, a horizontally disposed permanent horse-shoe magnet, a rotor disk on the shaft between the poles of said magnet, another horizontally disposed permanent horse-shoe magnet 10 in a different vertical position, a damping disk on the shaft between the poles of said other magnet, an externally threaded hollow stationary sleeve surrounding the shaft, an internally threaded disk of magnetic material 15 adjustably supported on said sleeve between the magnets, a graduated vertical scale at one side of said magnetic disk, said magnetic disk being provided with a set of equally spaced holes, and means for sealing 20 said disk in its adjusted position.

12. In a meter, a shaft, a rotor disk thereon, a magnet for said rotor disk, a damping disk on said shaft, a horse-shoe magnet having its poles extending over opposite sides 25 of the damping disk, ribbed pole pieces on the poles of said horse-shoe magnet, and a member of magnetic material adjustably supported between said magnets and adapted to influence both magnets.

30 13. In a meter, a vertical shaft, a mercury filled chamber, a rotor disk on said shaft immersed in the mercury in said chamber, a horizontally disposed stationary horse-shoe magnet with its poles extending

over opposite sides of the rotor disk, a damping disk on said shaft, a horse-shoe magnet having its poles extending over opposite sides of the damping disk, ribbed pole pieces on the poles of said horse-shoe magnet, and a vertically adjustable member 40 of magnetic material between said magnets.

14. In a meter, a vertical shaft, a mercury filled chamber, a rotor disk on said shaft immersed in the mercury in said chamber, a horizontally disposed stationary horse-shoe magnet with its poles extending over opposite sides of the rotor disk, a damping disk on said shaft above the rotor disk, a pair of magnets having like poles thereof facing one another, and their unlike poles extending over opposite sides of the disk, a hollow threaded sleeve surrounding the shaft above said rotor magnet, an internally threaded disk of magnetic material 45 adjustably supported on said sleeve, a graduated vertical scale at one side of said magnetic disk, said magnetic disk being provided with a set of equally spaced holes, and means for sealing said magnetic disk in its adjusted position.

50 In witness whereof, I have hereunto set my hand this 11th day of August, in the year 1913.

EDWIN H. MESSITER.
